UNITED STATES PATENT OFFICE.

JOHN GOOD, OF BROOKLYN, NEW YORK.

SPINDLE AND FLIER.

SPECIFICATION forming part of Letters Patent No. 349,709, dated September 28, 1886.

Application filed July 18, 1884. Serial No. 138,042. (No model.)

To all whom it may concern:

Be it known that I, JOHN GOOD, of the city of Brooklyn, in the county of Kings and State of New York, have invented a new and useful 5 Improvement in Spindles and Fliers, of which the following is a specification.

My invention relates to closed fliers and their spindles, such as are employed in spinning rope-yarn and for making twine. In machines 10 of this class the flier and spindle are commonly driven by separate belts from two pulleys on a counter-shaft driving onto two pulleys, one fast on the flier-journal and the other locked fast to the spindle, so that the spindle and its 15 pulley turn in unison. The flier has a uniform speed of rotation; but as the bobbin on the spindle increases in size the spindle should turn slower, and more power is required to drive it, because of the increasing leverage 20 which the yarn or twine exerts to retard the bobbin, and which must be overcome to maintain a uniform tension on the yarn or twine.

In order to provide for imparting the necessary variable movement to the spindle and bobbin it has been customary to employ a friction-drag consisting of a disk or flange and a 25 pulley having faces which are in frictional contact one with another, whereby the necessary slip between the pulley and the disk or flange 30 is provided for.

My invention relates to machines in which the friction device or drag is arranged directly in the spindle and flier, instead of upon a counter-shaft, as has also been done heretofore.

Important objects of my invention are to reduce the number of bearings necessary for the 35 spindle and flier and to provide a very compact arrangement of the bearings for the flier, the spindle, and the flier-driving pulley and 40 friction-disk; also, to provide a more desirable means than that heretofore in use for transmitting the movement of the traverse motion to the bobbin.

The invention consists in the combination, 45 with a spindle and flier, of a pulley on the flier-journal for driving the flier, a loose pulley concentric with the spindle for driving it, and a friction device or drag interposed between the spindle-pulley and the spindle itself.

The invention also consists in the combination, 50 with a spindle and a flier having a tubu-

lar journal at its driving-head and a driving-pulley fast thereon, of a spindle-driving pulley having a long sleeve fitting and turning in the interior of the tubular journal of the flier 55 and receiving the spindle through it; also, in the combination, with the foregoing, of a friction-disk working against a face provided in the spindle-pulley, locked to the spindle, and having a tubular sleeve receiving the spindle 60 through it, and fitting and capable of turning in a recessed portion or counterbore in the sleeve of the spindle-pulley, as more fully hereinafter described.

The invention also consists in the combination, 65 with a closed flier, fixed bearings for the journals thereof, and a hollow slotted spindle fitting bearings at opposite ends of the flier and adapted to receive upon it a sliding bobbin, of means, substantially as hereinafter described, for driving the flier and spindle, a bobbin-coupling fitted to slide on the spindle, and a traverse rod sliding loosely in the hollow spindle and having a head projecting 70 through the slot in the spindle and permanently connected with the bobbin-coupling.

In the accompanying drawings, Figure 1 is a vertical longitudinal section of a spindle and flier—such as are commonly used in “jenny” for spinning rope-yarns—and means for driv- 80 ing them, embodying my invention. Fig. 2 is a back view of the friction disk or flange and a transverse section of the spindle, showing the means whereby they are locked together. Fig. 3 is a back view of the bobbin-coupling and a 85 transverse section of the spindle and traverse rod; and Fig. 4 is a longitudinal section on a larger scale, illustrating the driving-head of the flier and the driving mechanism for the spindle and flier, also including the bearing 90 for the driving-head journal.

Similar letters of reference designate corresponding parts in all the figures.

A designates the flier, having at one end the capstan-head A' and journal B, and at the 95 other end the driving-head A² and journal B'. The journal B' consists of or is formed by a hollow hub or sleeve, which is fitted to a bearing, a, in a suitable frame, B², and on which is formed or secured a flier-driving pulley, C. 100 The journal B at the capstan-head A' of the flier is fitted to a bearing, a', on the frame B²,

and is tubular, so as to receive through it the shaft or stem a^2 of the capstan-pinion, on which is a pulley, a^3 .

D designates the spindle, which has a suitable bearing, a^4 , in the capstan-head A' of the flier, and is made hollow or tubular nearly or entirely from end to end.

E designates the bobbin, which is fitted to slide on the spindle, but is locked to turn therewith, as I shall soon describe, and F designates a spindle-driving pulley, which is concentric with the spindle and the flier-journal.

The pulley F is constructed with a long tubular sleeve, F', which is fitted to the interior of the hollow flier-journal B', and is afforded an adequate bearing therein. From its inner end outward for about half its length the sleeve F' is bored to fit the spindle D, and while the said sleeve is itself afforded adequate bearing in the flier-journal B' it affords ample bearing within it for the spindle. From the outer end of said pulley-sleeve F' inward for about half its length there extends thereinto a recess or counterbore, b, and on the outer side of the pulley F is a friction face or surface, b'.

G designates a friction disk or flange which bears against the face b', and is preferably faced with leather *, or other material to make frictional engagement with the pulley F. The friction disk or drag G', which is fitted to and afforded ample bearing in the recess or counterbore b, receives the spindle D through it. The spindle-pulley F, though it receives the spindle through it, is not locked thereto, but the friction disk or drag is locked to the spindle, so as to drive the same.

The spindle here shown has lugs or ears c at opposite points, and in the hub of the disk or flange G are notches c', which receive said lugs or ears and engage with them to drive the spindle.

The bobbin E is attached to a bobbin-coupling, E', also fitted to slide on the spindle D and detachably connected by means of an ear and slot, c² c* with the bobbin E.

H designates the traverse rod, which is fitted to slide within the hollow spindle D, and is moved therein longitudinally by any well-known traverse motion connected with its outer end, H'. This to-and-fro traverse motion may be produced by means of a screw having crossed threads of reversed pitch engaging a swiveled nut-section or fork carried by the sleeve, through which the screw extends, as is shown in my Letters Patent No. 317,116, dated May 5, 1885. The hollow spindle D is slotted at d for the greater part of its length, and the head H² at the inner end of the rod H projects through this slot and is permanently connected with or attached to the bobbin-coupling E' by a screw or other suitable means. The bobbin-coupling is locked to the spindle by the head H², passing through the slot d. The pin-and-slot connections c² c* between the bobbin and its coupling are well known, and are of such form that when the bobbin is turned ahead slightly

relatively to the coupling it may be separated therefrom.

I designates a counter-shaft, which is driven by a belt, I', over a pulley, I², and on said counter-shaft are two pulleys, I³ I⁴, from which belts I³ I⁴ drive onto the pulleys C F, which transmit motion to the flier and spindle. The pulleys I³ I⁴ are fast on the counter-shaft I, and the effects of the friction device or drag are transmitted directly to the spindle without any variation, and a uniform tension will be produced on the yarn or twine as it is wound on the bobbin. These important results are due entirely to the arrangement of the friction device or drag in the spindle and flier, and cannot be obtained when a belt is interposed between the friction device or drag and the spindle, as has been the case heretofore.

As the bobbin increases in diameter by the winding of the yarn or twine upon it the disk or flange G must be pressed more strongly against the friction-face of the pulley F, in order to overcome the increasing resistance to the rotation of the bobbin.

J designates a forked lever fulcrumed at e, and having a bearing on the hub of the disk G. The lower end of this lever is connected by a rod, J', with the short arm of a balance-beam, J², which is fulcrumed at e', and the long arm of which has an attached screw-shaft, J³, on which is suspended a weight, J⁴. The screw-shaft J³ derives a slow rotary motion by a worm-wheel, e², and worm e³, from a cross-shaft, e⁴, and this shaft e⁴ is rotated by belt or gearing from any convenient shaft of the machine. The weight J⁴ has a knife-edged bearing on the screw-shaft J³, and as the size of the bobbin increases the weight is moved outward on the long arm of the lever by the slow rotation of the screw-shaft. As the weight J⁴ moves outward it exerts a greater pressure of the disk G against the friction-face of the pulley F, and so exerts a greater power to turn the bobbin and spindle.

The mechanism above described for applying a gradually increasing pressure of the disk G on the pulley-face is well known in connection with machines having the friction device or drag on a counter-shaft and a belt interposed between the friction device and spindle, and I do not therefore claim the same, broadly.

On the counter-shaft I is still another pulley, I⁵, from which a belt, I⁶, drives onto the pulley a³ on the shaft a² of the capstan-pinion.

What I claim as my invention, and desire to secure by Letters Patent, is—

1. The combination, with a spindle and flier, of a pulley on the flier-journal for driving the flier, a loose pulley concentric with the spindle for driving it, and a friction device or drag interposed between the spindle-pulley and the spindle itself, substantially as herein described.

2. The combination, with a spindle and flier having a tubular journal at its driving-head and a driving-pulley fast thereon, of a

spindle-driving pulley having a long sleeve fitting and capable of turning in the tubular journal of the flier and receiving the spindle through it, substantially as herein described.

5. 3. The combination, with a spindle and a flier having a tubular journal at its driving-head and a driving-pulley fast thereon, of a spindle-driving pulley having a long sleeve fitting and capable of turning in said tubular flier-journal, and receiving the spindle through it, and a friction device or drag interposed between the spindle-driving pulley and spindle, substantially as herein described.

10. 4. The combination, with a spindle and a flier having a tubular journal at its driving-head, and a driving-pulley fast thereon, of a spindle-driving pulley having a long sleeve fitting and capable of turning in the tubular flier-journal and recessed or counterbored 15 from its outer end inward, and a friction disk or drag locked to the spindle, having a tubular

sleeve fitting the recess or counterbore in the sleeve of the spindle-driving pulley and bearing against a friction-face on said pulley, substantially as herein described.

25

5. The combination, with the closed flier, fixed bearings for the journals thereof, and a hollow slotted spindle fitting bearings at opposite ends of the flier and adapted to receive upon it a sliding bobbin, of means, substantially as described, for driving the flier and spindle, a bobbin-coupling fitted to slide on the spindle, and a traverse-rod sliding loosely in the hollow spindle and having a head projecting through the slot in the spindle 30 and permanently connected with the bobbin-coupling, substantially as set forth.
